UNITED STATES PATENT OFFICE.

WILLIAM SMITH, OF CAMBUSLANG, SCOTLAND.

LUBRICATOR.

1,010,195.

Specification of Letters Patent. Patented Nov. 28, 1911.

Application filed November 18, 1910. Serial No. 593,056.

To all whom it may concern:

Be it known that I, WILLIAM SMITH, having post-office address 164 Howard street, Glasgow, Scotland, valuator, a subject of the British King, residing at Cambuslang, Lanarkshire, Scotland, have invented certain new and useful Improvements in Lubricators; and I do hereby declare the following to be a full, clear, and exact description of the invention, such as will enable others skilled in the art to which it appertains to make and use the same.

The present invention relates to force feed lubricators of the spring pressed piston type, and has for its purpose to provide a lubricator of that character having a novel means for filling the same with lubricant and for causing its ejection under a constant uniform pressure.

With these and other objects in view the invention consists in the arrangements and combinations of parts hereinafter claimed, and while the invention is not restricted to the exact details shown and described, still for the purpose of disclosure reference is had to the accompanying drawing wherein the figure discloses the lubricator in central vertical section and with parts in elevation.

Referring to the construction in detail A is the cylindrical containing vessel of the lubricator.

B is the inlet by which oil is fed by way of the tubular passage C formed in the hollow stem C' of the upper piston D. Placed in the said inlet is a semi-spherical valve E. The semi-spherical valve has a depending stem F, around which is coiled a spring G. The opposite end of said stem F works through a hole or opening H which acts as a guide in the movement of the valve E when it is pressed from its seat in charging the lubricator.

I is the lower piston having a hollow stem or rod J adapted to move within its respective end of the cylinder and provides the discharge passage or outlet for the oil or

lubricant. Placed in said hollow stem is the valve K which terminates with a conical nozzle through which a passage L of small bore is formed. The oil or lubricant flows out through said passage and is controlled or regulated in its movement by a milled head K', in screwing the conical nozzle toward a transverse pin M or farther therefrom.

N is a lock nut for determining a set discharge.

O, P, are the spiral springs for pressing together the pistons and ejecting the lubricant.

What is claimed is:—

1. In a lubricator the combination of a cylinder, a piston mounted to move in said cylinder, a hollow piston rod connected with the piston and adapted to have movement through one end of the cylinder, a nozzle adjustably mounted in the end of said piston rod, a milled head for adjusting the position of said nozzle, a lock nut for holding said nozzle in adjusted position, a pin disposed transversely of and secured in said piston rod adjacent one end of the nozzle and cooperable with said end to regulate the flow of lubricant through the nozzle; and a spring surrounding said piston rod and exerting a constant pressure against the piston.

2. In a lubricator the combination of a cylinder, a pair of pistons mounted to move within the cylinder, a hollow piston rod secured to one of said pistons and extending through one end of the cylinder, said hollow piston rod providing a channel for supplying the lubricant to the cylinder, a valve comprising a semi-spherical head and a stem mounted within said piston rod, a spring surrounding the valve stem and normally tending to keep the valve head seated, a spring surrounding said piston rod and normally tending to exert pressure against the piston, a hollow piston rod connected with the other piston and mounted to have move-

ment in the end of said cylinder, a nozzle adjustably mounted in the end of said rod, a milled head for adjusting the position of said nozzle, a lock nut for holding said 5 nozzle in adjusted position, a pin disposed transversely of and secured in said piston rod adjacent one end of the nozzle and co-operable with said end to regulate the flow of lubricant through the nozzle; and a

spring surrounding said piston rod and exerting a constant pressure against the piston. 10

In testimony whereof, I affix my signature, in presence of two witnesses.

WILLIAM SMITH.
